UNITED STATES PATENT OFFICE

2,558,080

ELECTRIC ANT AND ROACH TRAP

Allen J. Gardenhour, Waynesboro, Pa.

Application August 3, 1945, Serial No. 608,798

7 Claims. (Cl. 43—112)

1

My invention relates to an electric ant and roach trap particularly adapted for killing insects of the crawling varieties, though well adapted also for destruction of other insects. It is an object of the invention to provide means of the character described that shall be simple, strong and compact, and therefore inexpensive to manufacture and not likely to get out of order.

Another object is to provide convenient means to contain the remains of dead insects, which means is so arranged as to be readily removable for disposal of such insects, such means being also adapted for holding bait to attract insects.

Another object is to provide means for supporting a transformer to step up the voltage of the electric current that is used in my device, with strong and simple means for supporting the transformer in a desirable position.

Referring now to the drawings, which are made a part of this application and in which similar reference characters indicate similar parts:

Figure 1 is a plan of one form of my invention;

Figure 2, an elevation of the same with parts in section;

Fig. 2a, a detail of parts shown in Fig. 2;

Figure 3, a bottom plan, omitting the lowermost member of the trap;

Fig. 4, a plan view of another form of the invention;

Fig. 5, a wiring diagram of Fig. 4, and

Figure 6, an elevation of still another form of the invention with parts in section.

In the drawings, reference character 10 indicates a pan that forms the bottom member of the trap. In a preferred form of the invention the remaining parts are supported in the pan by means of a frame comprising crossed strips of metal that fit closely enough in the pan to hold the parts securely together but so as to permit separation by the user, as by grasping the top of the device with one hand and the pan with the other. In the device as here shown the crossed members consist of a long strip 11 extending completely across the pan and two shorter strips 12, 12 each extending from strip 11 to the adjacent wall of the pan, the strips 12, 12 being riveted to strip 11 or otherwise permanently fixed thereto, and the outer ends of all these strips bearing against the inner wall of the pan.

A base 13 rests on the cross strips 11, 12, 12 and is fixed thereto by means of angular strips 14 of metal, each of which has one leg riveted to the base and the other to one of the strips of the frame, all parts of the device being made of sheet metal or wire unless otherwise indicated.

2

Upon the base and fixed thereto by means of screws 15 is the casing 16 of a transformer having a primary coil 17, a secondary coil 18 and an iron core 19, all as indicated in Fig. 5, the primary coil 5 being connected to a source of current by conductors 20 (Figure 2) and the transformer being fixed to the base by screws 20'. A lead 24 connects one pole of the secondary of the transformer to the ring 21, hereinafter referred to, and the lead is insulated from base 13 by an insulator at 25 (Fig. 3). Another lead C connects the opposite pole of the secondary to the base 13 through a screw 21'.

Within the wall of the pan 10 is a wire ring 21, suitably spaced therefrom to tend to contact insects on the wall of the pan, it being understood that the spacing may be varied according to need, as may other details of the trap. Usually the ring will be held at about the level of the verge of 15 the pan, as being the most effective position but this may be altered according to circumstances. The ring is carried by insulators in the form of porcelain bushings 22 having circumferential grooves to receive parts of the strip 11 or 12 by 20 which they are carried. It will be understood on consideration of the various figures that the strips have radial slots or cutouts S near their outer upper corners wide enough to admit the narrow mid-portion 23 of an insulator (Figure 2) 25 whose flanges D then hold it in place by engagement at the top and bottom and inner side with the edges of the cutouts, while the wire ring 21 prevents the insulator from leaving the cutout.

As a matter of convenience in assembling parts, 30 the insulators have holes considerably larger than the diameter of the wire of ring 21, and are held in place after assembly by means of inserts 26 of rubber cord or other like packing material.

In the operation of the device, assuming the 35 same to be connected to a source of current, and bait of any suitable kind having preferably been placed in the pan, if an insect attempts to crawl into or over the trap and if parts of the insect contact the pan and the wire ring 21, a current 40 of high voltage will pass through it and electrocute the insect, and the same thing will occur if it touches simultaneously any two oppositely electrified portions of the trap. The pan serves as a holder for bait, as a container for dead insects 45 and as one of the oppositely charged elements of the trap, besides serving as a support for the trap.

In the modified form of the invention, shown in 50 Fig. 4, the pan 30, the frame comprising the crossed strips 11', 12', and the transformer 31'

may be generally as in the form first described, but instead of a single wire ring there are several concentric wire rings 28 and 31. Of these, two rings 29 are grounded on the metallic frame as by being fixed directly to radial strips 11', 12', as shown, by welding, or clamping, etc. The wire rings 31 are insulated from the metal frame by flanged bushings 22' (Fig. 4). These bushings may be inserted into slots opening at the top of the radial frame members as indicated at 22a. The rings 31 are connected to one pole of the secondary of transformer 31' by a lead 33, whereas the rings 29 and the pan 30 are connected to the opposite pole of said secondary by a lead 32 (Fig. 5). In Fig. 4, the cross strip 11' is connected to the cross strips 12' in a similar manner as disclosed in Fig. 3 for the crossed strips 11 and 12. The base 13 shown in Figs. 1-3, inclusive, is omitted from the form shown in Fig. 4, and the transformer 31' is secured to the crossed strips 11' and 12' in Fig. 4, in any convenient manner.

In the second modified form shown in Fig. 6, grounded rings 34 bonded to the frame are arranged in alternation with insulated rings 35 in a vertical coaxial series, the rings being held as before by crossed frame members 36 and 37, and the grounded wire rings 34 being secured directly to said crossed pieces whereas the other rings 35 are set in insulators 22'' located in said frame members. The base 38 of the device stands in pan 39, which may serve as bait holder, dead insect holder and frictionally connected holder for the remaining parts of the trap, etc., as before. The frame is surmounted by a dome-shaped cover 40 with a guide eye 41 through which pass the conductors leading to a transformer shown generally at 42 and having leads connected respectively to the frame at 43 and to the insulated rings at 44, parts of the lower rings being omitted for better showing of the remaining lower parts of the trap. A light bulb may be located in suitable position, e. g., as shown at 45 in a socket 46 at the lower end of the trap, the inner ends of frame members 36 and 37 being omitted in part to afford space for the lamp. The frame 43 rests in pan 39, and includes the crossed members 36 and 37, similar to members 11 and 12 in Fig. 3. Since the pan 39, members 36 and 37, rings 34 and frame 43 are connected to one pole of the transformer secondary, while the other pole is connected to insulated rings 35 as at 44, any insect bridging two adjacent rings 34 and 35 short circuits the transformer secondary and is electrocuted.

An advantage of the construction of Figure 6 resides in the fact that it is well adapted for use against flying insects as well as crawling ones, in that insects contacting oppositely charged wires in the upper portions of the trap are killed with equal certainty as those crawling up over the rim of the pan.

It will be obvious to those skilled in the art that many changes may be made in the devices herein disclosed, all without departing from the spirit of the invention, and therefore I do not limit myself to what is shown in the drawings and described in the specification, but only as indicated in the appended claims.

Having thus fully described my invention, what I claim is:

1. An insect trap comprising a circular pan, a frame having radial members fitting frictionally in the pan, said pan and said frame being made of conducting material, a transformer located at the top of the frame, radial slots in the outer

ends of the radial frame members, insulating circumferentially grooved bushings in said slots and held against lateral displacement by engagement with said frame members, a wire ring carried by said bushings in concentric relation to the rim of said pan, an electrical connection from said frame and pan to one terminal of the secondary of the transformer and an electrical connection from the wire ring to the other terminal of the secondary of the transformer.

2. An insect destroyer comprising a circular pan, a frame having radial members adapted to stand in the pan, a transformer mounted on the frame, insulating bushings arranged in a circle substantially concentric with the rim of the pan on said radial members, a wire ring mounted in said bushings, electrical connections from one terminal of the secondary of the transformer to said wire ring, and electrical connections from the other terminal of the secondary of the transformer by means of the frame to the rim of the pan, both the pan and the frame being conductors of electricity.

3. An insect destroyer comprising a pan having a wall, a frame in the pan, means for supporting a transformer on the frame, a conductor arranged concentrically with the pan close to the rim of its wall, said pan and frame being made of conducting material and said conductor being insulated from the frame and pan, and connections from opposite terminals of the secondary of the transformer to the said conductor and to the pan respectively.

4. An electrical insect trap comprising a metallic pan, a metallic frame in the pan, means for supporting a transformer on the frame, a series of conductors arranged concentrically with the margin of the pan in spaced relation to each other and to the margin of the pan wall such as to be adapted to permit an insect to contact with adjacent conductors or with a conductor and the said margin, means for insulating alternate conductors from said pan and frame, means for connecting said insulated conductors to one terminal of the secondary of the transformer, and means connecting the pan and the remaining conductors to the other terminal of the secondary of the transformer.

5. An electrical trap comprising a circular metallic pan, a metallic frame having radial members fitting frictionally in said pan, a plurality of concentric sets of insulating bushings at spaced intervals on the radial members of said frame, concentric wire rings carried by the respective sets of bushings, other wire rings arranged in alternation with the first-named rings and bonded to said radial members, a transformer supported on said radial members and electrically connected at one terminal of the secondary of the transformer by way of said radial members to said pan and to the rings bonded to said radial members, and a connection at the other terminal of the secondary of the transformer to the wire rings mounted in said bushings.

6. An electrical insect trap comprising a metallic pan, a metallic frame in said pan, said frame having radial members, a transformer supported on said frame, a vertical series of insulating bushings at the outer end of each radial member, a series of vertically spaced wire rings in said bushings, wire rings bonded to said radial members between each successive pair of the first-named rings, all of said rings being coaxially arranged, 75 a transformer mounted on said frame and elec-

trically connected thereto at one terminal of the secondary, and means connecting the other terminal of the secondary of the transformer to the insulated rings.

7. An electric insect trap as in claim 6, the transformer being mounted at the top of the frame, and an electric lamp mounted inside the frame at the lower end thereof.
